BAG MACHINE

John Koenig, Philadelphia, Pa., assignor to Benjamin C. Betner Company, Devon, Pa., a corporation of Delaware

Application March 15, 1937, Serial No. 130,823

6 Claims. (Cl. 93—27)

My invention relates to machines for making paper bags, and particularly to mechanism for forming and closing the bottoms of bags.

In accordance with my invention, the bag blank is held, to structure for carrying it adjacent bottom-forming and closing mechanism, by grippers at least one of whose jaws is provided with blunt abutments or projections which clamp upon a crease in the bag blank forced between the jaws by a tucker blade having notches in alignment with the projections on the gripper jaws and which is withdrawn after the jaws have closed to clamp the bag blank.

My invention further resides in the features of construction, combination and arrangement hereinafter described and claimed.

For an understanding of my invention and for illustration of a preferred form thereof, reference is made to the drawings in which:

Fig. 1 is a plan view of bag-closing mechanism;

Fig. 2 is a side elevation, with parts in section, of mechanism shown in Fig. 1;

Fig. 3, in perspective, shows parts appearing in Figs. 1 and 2;

Fig. 4 is a section, on enlarged scale, illustrative of gripper mechanism shown in Figs. 1-3;

Fig. 5 is a detail, on enlarged scale, of cam structure shown in Figs. 1-3;

Fig. 6 is a perspective view of a bag blank.

Referring to Figs. 1 and 2, the mechanism disclosed is generally of the character illustrated in Potdevin Patent #1,176,163 for forming and closing the bottom of a bag blank, for example, of the well-known tubular type, such as blank B, shown in Fig. 6 hereof.

The blanks are formed by mechanism not herein disclosed, and each in turn is fed with the flap F thereof presented to the cylinder or drum 1 attached to shaft 2 which is supported by the side frames 3 of the machine. The fingers 4 which extend through gap 5 in the periphery of the drum 1 clamp the flap F of the blank to the drum for movement therewith as the drum rotates in counterclockwise direction, as viewed in Fig. 2. The fingers 4 are carried by blocks 6 on shaft 7 which rotates with the drum 6 and is rocked in timed relation thereto by cam structure not herein shown, but whose construction and operation are well-known to the art as illustrated, for example, by the aforesaid Potdevin patent.

To shaft 8, which is supported above shaft 2 by the side frames 3, are secured the supporting members 9, 9 which carry the tucker blades 10 and 11.

As the drum 1 rotates in counterclockwise direction the blank B whose flap F is held to the drum by fingers 4 is drawn upwardly beneath the weighted holding fingers 26 and concurrently the shaft 8 is rotated in opposite direction, the timing between the shafts being such that the tucker blade 10 engages the moving blank B substantially along the line marked x, Fig. 6, and forces the blank between the jaws of the gripper G which are at this time open. As movement of drum 1 continues, the jaws of the gripper G are closed by cam mechanism not herein disclosed, but generally as illustrated in the aforesaid Potdevin patent; the timing being such that the tucker blade 10 is withdrawn before or substantially concurrently with closure of the gripper jaws.

As drum 1 and shaft 8 continue their rotation, the second tucker blade 11 engages the blank B along the line marked y, Fig. 6, and forces the blank along this line between jaws of the gripper G1 which are opened somewhat before the blade and jaws are in substantially vertical alignment. The blade 11 creases the blank at y and forces the crease between the gripper jaws thus to form a shallow but thick multi-ply crease or fold. The gripper G1 comprises a relatively stationary jaw member 12 carried by the arm 13 which is rotatable with the drum but may be adjusted angularly with respect thereto and a movable gripper jaw 14 attached to shaft 15 which also rotates with the drum 1. The gripper jaws 12 and 14 are biased toward engagement with each other by the powerful spring 16, one end of which is suitably attached to shaft 15 and the other end of which is secured to the drum 1. Preferably, the tension of spring 16 is adjustable to permit variation of the clamping pressure to suit bags of different grades and finish of paper. From the shaft 15 extends an arm 17 having a cam follower or roller 18 in whose path of movement is disposed the cam 19 adjustably secured to a stationary member 3a attached to the machine frame.

Cam 19 is so adjusted the jaws 12 and 14 of gripper G1 are separated, as above stated, somewhat before the bag blank B carried by drum 1 arrives at such position the tucker blade 11 engages the blank along line y. The jaws 12 and 14 remain separated until the tucker blade 11 has pressed the crease at y between the gripper jaws; before the blade 11 is withdrawn, the roller 18 passes abruptly off the end of cam 19 to close the jaws upon the crease.

As most clearly appears from Figs. 1, 3 and 4,

the tucker blade 11 is provided with notches or recesses 20 which are in alignment with blunted teeth or projections 21 which extend a short distance from the gripping surface of movable jaws 14 towards the gripping surface of the stationary jaw 12. By so constructing the gripper jaws and the tucker blade, it is possible to effect closure of the gripper G1 securely to hold the bag blank before the tucker blade is withdrawn and notwithstanding the thickness of the crease y. This has not been possible with prior constructions in which both grippers G and G1 were substantially identical, and in which both tucker blades 10 and 11 were substantially identical. In the construction illustrated, the gripper G and tucker blade 10 are of conventional construction; because of the relatively few folds or thicknesses of paper at the crease x, it is possible so to adjust the clamping pressure of the gripper jaws and the timing of the grippers and tucker blade that there is no tendency for the blank to release from the gripper G during withdrawal of blade 10 or during the subsequent operations. However, at the crease y, the number of thicknesses of paper is materially higher, and is often or usually so great the thickness of the crease y, as shown in Fig. 4, is of the same order of magnitude as the depth of the crease with the result, and particularly when the paper is of waxed, lacquered or glazed finish, or when the external bag is of material, as cellophane, or the like, great difficulty has been experienced in so adjusting the machine that the bag blanks would not release at y during the bag-forming and closing operations. In general, the surfaces above mentioned have low coefficient of friction, and securely to hold the bag a high degree of pressure is required particularly because jaws of gripper G1, whether of the old or new construction, can at most merely nip the blank at crease y. With prior constructions, when the pressure was adjusted to value high enough to prevent the bag from following the blade as it was withdrawn, the surface of the bag was often badly marred or torn, whereas, unless high pressure were used, the bag would be insecurely clamped and would release during subsequent operations often with damage to the mechanism. It was difficult, and for some bag materials, practically impossible to obtain an optimum adjustment of the gripper corresponding in general purpose to G1 hereof; furthermore, when such optimum adjustment was obtained, there was no assurance it would not be necessary to repeat the tedious procedure before the end of the run because of the effect of atmospheric conditions upon the bag material and/or upon the machine parts.

With the gripper construction illustrated, the bag blank is securely held by the toothed projections 21 of gripper jaw 14 and the pressure upon the crease y is more or less, though not entirely, localized at these areas. The pressure at these points is not in full impressed upon the tucker blade 11 because of notches 20 therein which are in alignment with the projections 21. Because the projections 21 extend but slightly from the gripping face of jaw 12 and because of the yielding nature of the thick fold or crease y, the gripper jaws 12 and 14 are effective throughout their length to hold the crease y although the gripping pressure is at least initially higher at the blunt projections 21. As the blade is withdrawn, the tendency of the blank to follow or tend to follow the tucker blade is insubstan-

tial and may be overcome by adjustment of the spring pressure to a value insufficient to mar the bag surface even when highly glazed.

Preferably, as shown in Fig. 3, one and preferably both of the jaws of the gripper G1 are divided, as by notches 25 from their outer edges, into several fingers; specifically, in Fig. 3, the fingers 22 of the movable blade 14 formed by the notches 23 in the blade are opposite or in alignment with the fingers 24 formed by the notches 25 in the fixed blade 12. The division of each of the gripper jaws 12, 14 into sections, which are at least to slight extent capable of relative flexure, facilitates an adjustment of the mechanism which will permit the clamping pressure to be adjusted to value suitable to prevent the blank from following the tucker blade 13 as it withdraws from the crease, without being so high as to mar or mark the blank. When the jaws of gripper G1 are closed upon fold or crease y, all fingers of the jaws are effective to exert substantial clamping pressure upon the crease; specifically the central section or finger 22 of jaw 14 which is devoid of projections 21 is effective to press that portion of crease y between projections 21 against the central section 24 of jaw 12, and the areas of the outer fingers 22 beyond the projections 21 are effective to press those portions of crease y beyond the projections 21 against the corresponding areas of the fingers 24 of the fixed jaw 12.

The mechanism for applying adhesive or paste to the portion b of the blank between the creases x and y, and for subsequently folding the flaps F and F1 to seal the bottom of the bag, is not herein shown because it may be of known construction as exemplified, for example, by the aforesaid Potdevin patent; the flap F1 is folded into engagement with the pasted surface of the bottom section b of the bag by the folding bar 27 which extends between the chains 28, 28a adjacent the opposite side frames of the machine and engaged by sprockets 30, 31 on shafts 32, 33. The mechanism for applying the second flap F, not shown, may be of any suitable type, such as illustrated, for example, in aforesaid Potdevin patent.

What I claim is:

1. A bag-forming machine comprising bag-closing mechanism, structure for transporting a bag-blank toward said mechanism, means carried by said structure for clamping the leading end of said blank, mechanism securely to hold the bag-blank, for operation thereon of said bag-closing mechanism, without marring the bag comprising gripper jaws carried by said structure, at least one of said jaws having blunt projections extending from its gripping face toward the other jaw, for engaging the blank while held to said structure by said clamping means, and blade structure, having notches straddling said projections, for tucking the blank, beyond the clamped leading end, between said gripper jaws for engagement by the gripping faces thereof and by said projections therefrom.

2. A bag-forming machine comprising bag-closing mechanism, structure for transporting a bag-blank toward said mechanism, means carried by said structure for clamping the leading end of said blank, mechanism securely to hold the bag-blank, for operation thereon of said bag-closing mechanism, without marring the bag comprising gripper jaws carried by said structure, at least one of said jaws having blunt projections extending from its gripping face toward the other jaw for engaging the blank while held

- to said structure by said clamping means, blade structure, having notches straddling said projections, for tucking the blank, beyond the clamped leading end, between said gripper jaws 5 for engagement by the gripping faces thereof and by said projections therefrom, and means adjustable to determine the pressure of said gripper jaws on the tucked-in portion of the bag blank.
3. A bag-forming machine comprising structure for transporting a bag-blank, bag-closing mechanism operating upon said blank during its transport by said structure, mechanism to hold the bag-blank for operation thereon of said bag-closing mechanism comprising relatively 10 movable gripper jaws carried by said structure, and blade structure for creasing the bag-blank during its transport by said structure to form a thick, multi-ply fold between said gripper jaws, at least one of said jaws having projections extending a short distance from its gripping surface toward the gripping surface of the other jaw to compress said thick fold at localized areas, said gripping surfaces exerting substantial pressure along said fold where not locally compressed by 15 said projections, and said blade structure having notches to straddle those sections of the fold compressed by said projections.
4. A bag-forming machine comprising structure for transporting a bag-blank, bag-closing mechanism operating upon said blank during its transport by said structure, mechanism to hold the bag blank for operation thereon of said bag-closing mechanism comprising relatively movable gripper jaws carried by said structure, at least 20 one of said jaws having slots subdividing it into gripping fingers, and blade structure for creasing the bag-blank during its transport by said structure to form a thick, multi-ply fold between said gripper jaws, at least some of said fingers having projections extending from their gripping surface toward the gripping surface of the other jaw to compress said thick fold at localized areas, 5 said fingers where devoid of projections exerting substantial pressure along said fold where not locally compressed by said projections, and said blade structure having notches to straddle those sections of the fold compressed by said projections.
5. A bag-forming machine comprising structure for transporting a bag-blank, blank-holding means movable with said structure comprising gripper jaws at least one of which has notches 10 extending inwardly from the edge thereof, and at least one of which has blunt projections extending from its gripping face toward the other jaw, and blade structure for tucking the bag-blank between said jaws having notches in substantial alignment with said jaw notches and for clearing said projections when the unnotched portions of the blade are embraced by unnotched portions of the jaws.
6. A bag-forming machine comprising a rotatable drum for transporting a bag-blank, blank-holding means movable with said drum comprising gripper jaws at least one of which has ridges extending from its gripping face and in direction substantially radial to the axis of rotation of 25 said drum and both of which have aligned slots adjacent said ridges, and blade structure for tucking the bag-blank between said jaws having notches for clearing said projections and unnotched sections which are embraced by those sections of the gripper jaws between the slots thereof.

JOHN KOENIG.
